US0D1057755S

(12) **United States Design Patent** (10) Patent No.: **US D1,057,755 S**
(45) Date of Patent: ** Jan. 14, 2025

(54) **DISPLAY SCREEN OR PORTION THEREOF WITH A GRAPHICAL USER INTERFACE**

(71) Applicant: **Beijing Zitiao Network Technology Co., Ltd.**, Beijing (CN)

(72) Inventors: **Chenxuan Zhao**, Beijing (CN); **Yijie Li**, Beijing (CN)

(73) Assignee: **BEIJING ZITIAO NETWORK TECHNOLOGY CO., LTD.**, Beijing (CN)

(**) Term: **15 Years**

(21) Appl. No.: **29/855,288**

(22) Filed: **Sep. 30, 2022**

(30) **Foreign Application Priority Data**

Apr. 6, 2022 (CN) 202230190042.1

(57) **CLAIM**

The ornamental design for a display screen or portion thereof with a graphical user interface, as shown and described.

DESCRIPTION

The FIGURE is a front view of a display screen or portion thereof with a graphical user interface showing the new design.

The outermost broken line in the FIGURE shows a display screen or portion thereof, and forms no part of the claimed design. The letter "X" and the Chinese letters/characters/symbols in the FIGURE show portions of the graphical user interface that form no part of the claimed design.

1 Claim, 1 Drawing Sheet
